CLAIM

The ornamental design for a pole mounted slipfitter for supporting exterior lights, as shown and described.

DESCRIPTION

FIG. 1 is a top, front, right side isometric view of a pole mounted slipfitter for supporting exterior lights showing a first embodiment of my new design;

FIG. 2 is a top plan view thereof;

FIG. 3 is a front side elevation view thereof;

FIG. 4 is a right side elevation view of a pole mounted slipfitter for supporting exterior lights showing the first and second embodiments of my new design;

FIG. 5 is a bottom plan view of a pole mounted slipfitter for supporting exterior lights showing the first and second embodiments of my new design;

FIG. 6 is a top, front, right side isometric view of a pole mounted slipfitter for supporting exterior lights showing a second embodiment of my new design;

FIG. 7 is a top plan view thereof;

FIG. 8 is a front side elevation view thereof;

FIG. 9 is a top, front, right side isometric view of a pole mounted slipfitter for supporting exterior lights showing a third embodiment of my new design;

FIG. 10 is a top plan view thereof;

FIG. 11 is a front side elevation view thereof;

FIG. 12 is a right side elevation view thereof; and,

FIG. 13 is a bottom plan view thereof.

The rear and left sides of each embodiment are mirror images of the front and right sides, respectively.
